UNITED STATES PATENT OFFICE

ALBERT D. WALKER, OF MIDDLEBORO, MASSACHUSETTS

DIE FOR MAKING ICE BAGS, ETC.

Application filed July 1, 1932. Serial No. 620,555.

This invention relates to dies for making ice bags, ice caps, etc.

An object of the invention is the production of simple and efficient means for tightly sealing the metal neck and fabric or rubber part of an ice bag or ice cap together.

Another object of the invention is the production of dies for making my type of a tight seal around my style of a metal neck of the rubber or other suitable fabric ice bag or ice cap where the metal joins the neck portion of the bag.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a vertical sectional view of a mechanism constructed in accordance with the present invention.

Figure 2 is a vertical sectional view of another embodiment of the auxiliary unit, showing the primary unit in dotted lines.

Figure 3 is a vertical sectional view of another embodiment of the auxiliary unit, while

Figure 4 is a top plan view of the die thereof.

Figure 5 is a perspective view of another embodiment of the auxiliary unit, while

Figure 6 is a sectional view taken on line 6-6, Figure 5 and looking in the direction of the arrows.

Figure 7 is a view in elevation of my ice bag.

Figure 8 is a perspective view of my ice cap.

Referring to the drawings by numerals, 1 designates the male or primary unit and 2 the female or auxiliary unit of the mechanism. The primary unit 1 is carried by the head 3 of a power press, while the auxiliary unit 2 is supported upon the base 4 of the power press.

The primary unit 1 comprises a stripper bar 5, mounted on the head 3, and is capable of an upward and a downward movement on

the head limited to about an inch and a half; said bar 5 is positioned above the horizontal extension 6 of head 3, with a space between said bar 5 and this extension, for the purpose hereinafter described. A punch 7 is located centrally of head 3 and is fixedly secured thereon. A stripper 8 is slidably mounted on punch 7; this stripper comprises a sleeve-like body 9 provided at its lower end with a horizontal annular flange 10 and at its upper end with a plate-like top 11. An annular groove 12 is formed in the lower face of flange 10, into which groove 12 fits the annular bead on the metal ring shown resting on the upper surface of the die 19. It is necessary to preserve this annular bead, by such fitting, as said bead is necessary to my finished ice bag or ice cap. Rivet bolts 13 are slidably mounted upon extension 6; these bolts have the top plate 11 of the stripper 8 mounted on their lower headed ends 14, Fig. 1, whereby the stripper is fixedly secured to bolts 13. The upper or inner ends of bolts 13 extend into the space between extension 6 and bar 5, with nuts 15 threaded thereon. The inner ends of bolts 13 are adapted to strike against stripper bar 5, for the purpose hereinafter described.

The auxiliary unit 2 shown in Fig. 1 comprises a swinging die bed 16, which is held in place upon base 4 by means of an anchor bolt 17; this bolt 17 allows the die bed to swing out from under the primary unit 1, while the ice bag is being positioned on the auxiliary unit, or removed entirely therefrom. The die bed 16 is provided with an upstanding portion 18 in which is securely seated closing-in die 19. The die 19 is internally tapered or bevelled at 20. A stop 21 is fastened to the top of base 4 against which the die bed 16 strikes when the die bed is moved to its proper position upon base 4, under the primary unit 1.

The operation of the embodiment shown in Fig. 1 is as follows: An ice bag 22 with the neck and ring already in place but not closed in, is put in the die 19, while the die bed 16 is swung outwardly, and then the die bed is swung inwardly until it engages stop 21. When the neck and ring, with the bag, are

placed in the die 19 just before the press is tripped, the ring 20 at the bottom has about the same or a slightly smaller diameter than the upper diameter of the opening in die 19. 5 All is then in readiness to trip the press. Upon tripping the press, the primary unit 1 comes down and punch 7 slides snugly into the metal neck 23 of the bag 22 until it is protecting all the neck threads 24. While 10 the punch 7 is thus entering, stripper 8 has engaged the top of the metal neck 23 and is sliding back along the punch 7 until it is brought up against the head of the press which condition will occur at the same instant 15 that the punch 7 has completely protected the neck threads 23. The whole primary unit 1 then continues downward, taking with it the ice bag into the bevelled portion 20 of the die 19, forcing the metal ring 20 to close in against the rubber material as shown in Figs. 1 and 2; the inside punch 7 in the meantime holds the metal neck in place. It is to be understood that at the beginning 25 of the stroke, the stripper bar 5 rests upon stripper bolts 13, and as stripper body 9 moves back along the punch 7, the bolts 13 naturally push the stripper bar 5 back the amount equal to the extent that the punch 7 goes into the neck of the bag, 30 Figs. 1 and 2. Then on the return stroke, the bag 22 is drawn back with the punch 7 almost to the full extent of the return stroke of the head 3. Before reaching its full extent, however, stripper bar 5 engages the 35 regular adjustable stripper stops (not shown) on the press. Stripper sleeve or body 9 not being permitted to move any further in an upward direction, necessarily remains stationary while the head 3 continues to the full extent of the backward stroke, 40 and withdrawing punch 7 from the neck of the bag 22. Die bed 16 is then drawn back, away from under the primary unit, and the bag is then removed or withdrawn. It is 45 noted that a portion of the metal neck 23 fits snugly into the annular groove 12 of the stripper 8, during the operation.

Figure 2 represents the punch 7 (dotted lines) at the fullest extent of the downward stroke. The stripper plate 11 is then against head 3. The operation is as follows: Because the ring used on this type of ice cap is much narrower than the one used in the other type bag, the distance which the neck has to travel downward in die 36 is much shorter. When the metal neck and ring are put together and placed in the die 34, the ring, because it is absolutely straight at this stage, can only 50 be forced by hand about half way into the curved surface of die 34 and leaving the rest of the distance to be forced by the overhead assembly. From this point it will be noted that punch 7 enters into the neck on 55 the downward stroke, practically, but not

quite, to the full extent of the neck. By this time, the stripper has gone back to the face of the head 3, which, by the way, is almost at the lowest point in its downward movement. The whole assembly, therefore, moves to the full extent of the stroke. This last distance is very short for, as can be readily seen, that due to the curved surface of the die 34, the ring closes in very rapidly in the remaining short downward movement. 70

In the embodiment shown in Fig. 5 of the auxiliary unit, the die bed 25 is provided with an upstanding platform 26, which platform is also provided, at two of its edges, with upstanding parallel flanges 27; the inner face of each flange 27 is inclined at 28; the two faces 28 constitute a dovetail effect. A two part die 29 is positioned between flanges 27 with their ends bevelled to correspond with the faces 28. At one end of flanges 27 is placed a transverse plate 30, which is held in position by screws 31. On the platform 26 is an eccentric cam 32; this cam 32 is provided with handle 33. The cam 32 normally presses against one of the sections of the die 29, holding the sections tightly in position, bearing against transverse plate 30. This die or auxiliary unit is for closing in the metal part of ice bags that employ a less pliable rubber fabric or material. The same primary unit 1, as shown in Fig. 1, is employed in conjunction with this auxiliary unit. Because of the much harder blow that this material requires, the bag instead of being withdrawn by the punch 7, as in the case described in connection with the embodiment shown in Fig. 1, it sticks in the lower die 29. In order to easily withdraw the work, this type of an auxiliary unit was devised; this method allows the sections of the die 29 to spread when the punch is withdrawn, thus permitting the completed ice bag to be taken from the auxiliary unit, in the same manner specified in connection with the embodiment shown in Fig. 1. 100

In the embodiment shown in Figs. 2 to 4, the same primary unit 1 is employed. The auxiliary unit of this embodiment is supported by the base 4, and comprises a two part or sectional die 34, which is internally bevelled at 35. A die holder 36 is placed upon the sections of the die 34, holding the same together. This device is adapted for attaching the metal neck and ring to the flat or moulded type of ice cap. The operation is as follows: The ice cap 37 is placed on the base 4 with the die 34 thereon, as shown in Fig. 2; this placing is done by the operator. The rubber neck of the cap slides 110 into the die 34 to its fullest extent. The metal neck and ring are then put together and placed in the die 34, letting the rubber neck protrude up into and between the neck and ring. The press is then released and 115

the primary unit 1 performs the same function as in the other embodiments, except that it does not bring back the completed cap with it, because of the fact that this 5 moulded rubber does not require a strenuous blow. The neck, therefore, does not cling to the punch 7. The cap 37 now being completed, holder 36 is pried off, by hand, off of the die 34; this die 34 is then separated and 10 finished cap taken off the die bed.

In the following claims, the base 4, or that which carries or supports the auxiliary unit may be referred to as a "support".

I have found from extensive use that my 15 embodiments perform in actual practice their results or operation in an exceedingly efficient manner.

While I have described the preferred embodiments of my invention and illustrated 20 the same in the accompanying drawings, certain minor changes or alterations may appear to one skilled in the art to which this invention relates during the extensive manufacture of the same, and I, therefore, reserve 25 the right to make such changes or alterations as shall fairly fall within the scope of the appended claims.

What I claim is:

1. In a mechanism of the class described, 30 the combination of a head provided with a horizontal extension, a stripper bar a considerable distance above said extension and on said head, a punch in the center of said head, a stripper slidably mounted on said 35 punch, said stripper comprising a sleeve-like body provided at its lower end with a horizontal annular flange, said flange provided with an annular groove in its under face, said sleeve-like body provided at its 40 inner or upper end with a plate-like top, vertical bolts having said plate-like top on their lower ends, said bolts loosely extending through said horizontal extension, nuts on the upper ends of said bolts between said 45 horizontal extension and said stripper bar, said bolts adapted to have their inner ends strike against said stripper bar for causing a bag to be knocked off said punch, and a bag-carrying auxiliary unit positioned under said head and punch and adapted to co- 50 operate therewith, substantially as shown and described.

2. In a mechanism of the class described, the combination with a head provided with extensions, of a single stripper bar on said head parallel to said extensions, a solid punch depending from said head, a stripper 70 longitudinally movable of and mounted on said solid punch, said stripper provided with means parallel with said extensions and with said stripper bar, means attached to said parallel portions of said stripper and extending through the extensions of said head and normally free from but being capable of engaging said single stripper bar for moving said stripper downward upon said punch, and an auxiliary die unit under said head 75 and punch. 80

3. In a mechanism of the class described, the combination of a head provided with an extension, a solid depending punch secured upon said head, a single stripper bar above 85 said extension of the head, a stripper slidably mounted on said solid punch, bolt-like members attached to said stripper and extending through the extension of the head and free at their inner ends from said single 90 stripper bar but being adapted to engage said stripper bar for moving said stripper for kicking a bag or cap off the outer end of said punch, and an auxiliary die unit under said head and punch. 95

4. In a die mechanism for making ice bags, the combination of a depending head provided with a broad extension at its lower end, a solid depending punch extending only from the center of said head and extension, a single stripper bar of the same width as said extension and positioned on said head above said extension, a stripper slidably mounted on said solid punch and provided with a plate-like top of substantially the 100 same width as said extension and stripper bar, bolts fixedly secured at their lower ends to said plate-like top and extending through said extension of the head, and said bolts free from said stripper bar but adapted to engage 105 said stripper bar at their inner ends for kicking a bag or cap off the outer end of said punch. 110

In testimony whereof I hereunto affix my signature. 115

ALBERT D. WALKER.
